UNITED STATES PATENT OFFICE.

HENRY DARBY, OF LONDON, ENGLAND, ASSIGNOR TO WILLIAM CHARLES PUNCHARD, OF SAME PLACE.

ARGAND LAMP.

SPECIFICATION forming part of Letters Patent No. 650,307, dated May 22, 1900.

Application filed September 1, 1899. Serial No. 729,222. (No model.)

To all whom it may concern:

Be it known that I, HENRY DARBY, manufacturer, a subject of the Queen of Great Britain, residing at 249 Pentonville road, King's Cross, London, England, have invented certain new and useful Improvements in or Relating to Hydrocarbon Circular-Wick Lamps and Burners, of which the following is a specification.

10 This invention has for its object improvements in or relating to hydrocarbon circular-wick lamps and burners, the light produced being of great brilliancy with economy of consumption of oil, while novel and striking effects are produced, the flame having very much the appearance of the present well-known incandescent gas-burner with mantle, although no mantle is used or intended to be used with the present invention, and by this 15 invention an incandescent-like mantleless oil-lamp is thus produced with great brilliancy of light.

Referring to the accompanying drawings, in which the present invention is illustrated, 20 Figure 1 is a view in elevation of a circular-wick hydrocarbon-burner, partly in section. Fig. 2 is a vertical sectional view taken through the diameter of said circular-wick oil-burner. Fig. 3 is a plan view of said 25 burner. Fig. 4 is a separate view of the central cone or restrictor for use in the central air-passage of said oil-burner. Fig. 5 is a view similar to Fig. 2, but showing a modified 30 form and arrangement of the interior restrictor-cone and flame-spreader. Fig. 6 shows another modification of the cone and flame-spreader thereon, and Fig. 7 shows still 35 another modification. Fig. 8 is a view in elevation of a complete lamp constructed according to the present invention, with an ornamental open-work restrictor B^x instead of the wire-gauze restrictor B shown in Figs. 1 and 5.

Similar letters of reference indicate corresponding parts throughout.

A is the lower part of the circular burner, having screw-threaded part A' adapted to screw into any suitable oil-reservoir of the ordinary or any suitable type—such, for instance, as the oil-reservoir X (shown in Fig. 5)—or this lower part of the burner may be

mounted upon or secured to the reservoir in any suitable manner other than by screwing, if desired.

A² is an upwardly-extending screw-thread 55 on the part A, adapted to have screwed thereonto the circular collar B', on which latter is mounted or secured the cylindrically-shaped restrictor B, of wire-gauze, or ornamental open-work restrictor B^x of cylindrical shape, 60 (shown in Fig. 5,) to the upper part of which open-work or gauze B is attached the collar B², which latter carries the chimney-gallery C, together with the circular hood D, as shown in Figs. 1 and 2, between the outside of which 65 hood D and the gallery C an ordinary straight-through—i. e., cylindrical—glass chimney Z or other suitable chimney is carried.

The aforesaid part A may be formed either so as to be suitable for use with the well-known central draft through the reservoir X or with the well-known form of wick-tube illustrated in the drawings—namely, the outer and inner circular-wick tubes E and F have the aperture Y formed through same, so 70 as to allow an ample supply of air to pass up the center of the said wick-tubes, and these said circular-wick tubes E and F are mounted and secured rigidly on the upper side of the aforesaid part A of the burner. 75

G is a circular inwardly-projecting flange carried on the inside of the upper collar B², so as to thus limit the size of the annular space between same and the outside of the upper part of the outer wick-tube E. 80

Within the inner wick-tube F is arranged and mounted a suitable restrictor H or means to regulate the central draft passing up the inside of the inner wick-tube F to the interior of the flame, such restrictor H being advantageously in the form shown in Fig. 4—namely, the lowermost part thereof adapted to fit closely inside the wick-tube F and rest on a shoulder F', formed inside said tube F, and then said restrictor H is formed tapered 95 and perforated at H' and at the upper part thereof is closed by the cap or cover H², and, if desired, the upper part of said device H may be expanded or provided with a disk or a flange, such as H^x, or other "flame-expander" adapted to tend to spread the flame outward, the position of this top of the re-

strictr H being substantially on a level with the top edge of the hood D, or just below same, or thereabout. Thus a regulated and restricted amount of air can pass up to the exterior of the flame, and also a regulated and restricted amount of air can pass to the interior of the circular oil-flame, the first-named air-supply through the annular passage *a* being limited by the flange G and the second-named air-supply through the central passage *b* being limited by the restrictor H.

I is the circular wick in the wick-tubes E and F, and J is an ordinary "wick-raiser" for raising and lowering the wick in any well-known or suitable manner. Thus the whole of the parts exterior of the wick-tubes E and F are formed cylindrical, of very narrow diameter, and are very compact and enable the use therewith of the fittings (gallery and globe, 15 chimney, &c.) of the aforesaid well-known type of incandescent gas-burners with mantle.

An important and essential part of the present invention consists in the arrangement and disposition of the various parts relatively to one another, and especially the arrangement of the hood D relatively to the wick-tubes E and F and the height to which said head D is carried above the top of the wick I in the wick-tubes E and F and also in the regulated air-supply to the exterior and to the interior of the flame, respectively, and also to the relative position of the flange G with respect to the top of the wick-tubes and its distance from the exterior of said tube E. The aforesaid annular space or opening between the inside wall of the hood and the outside wall of the wick-tubes is of sufficient size to allow an ample supply of air to the exterior of the flame. Also instead of mounting the expander H^X directly on a perforated cone or device, such as H H', as aforesaid, said restrictor or device, such as H H', may be made separately and arranged lower down in the wick-tube F, and the expander H^X would then be supported in any suitable manner—such, for instance, as a central pillar—in the aforesaid position—namely, at or about the same horizontal plane as the top edge of the hood D—and either combined with or independent of the restrictor H H'. Such an arrangement is shown in Figs. 5 and 6. In Fig. 5 the restrictor-cone H' has the button or flame-spreader H² on the apex of said cone. In Fig. 6 the restrictor H' is in the form of a truncated cone, with the spreader H² carried on a movable central vertical post H³, and in Fig. 7 the arrangement is similar to Fig. 6, except that the vertical post H³ is fixed. Thus it will be seen that in this burner with straight chimney air can only obtain access to the interior of said chimney through the said basket B, and thence is directed partly through the interior of the wick-tube—i. e., through the passage *b*—and partly through the annular space or passage *a*, as aforesaid, and, if desired, a series of holes D^X may be provided in the lower part of the hood D, some of said holes D^X leading to the interior

of the aforesaid straight chimney Z at or near the bottom of the latter and between same and the outside of the hood D and some leading to the exterior of said chimney Z, the object of these holes D^X being mainly to keep the burner cool. Thus by the present invention a circular flame is produced in a hydro-carbon-lamp which assumes the same or a very similar shape and appearance to the appearance and shape of the well-known incandescent gas-burner with mantle, as indicated in dotted lines at W in Figs. 2 and 5, intense light being produced with great economy of consumption of oil, further advantages being that said light can be regulated—i. e., can be turned down—whereupon the lamp will burn without smell even when turned down quite low, while the container or oil-reservoir X always keeps cool.

By forming the chimney Z of perfectly clear glass from the bottom thereof up to the line V V, (see Fig. 5,) or thereabout and then forming said chimney Z semitransparent or translucent or even opaque above line V V thereby the aforesaid imitation incandescent-like appearance is heightened, since the top-most part of the flame W is hidden by the said non-transparent part of the chimney Z.

Having now described my invention, what I claim as new, and desire to secure by Letters Patent of the United States, is—

1. The combination with a circular-wick oil-burner, having a hood such as D extending above the top of the wick-tubes, a restrictor such as B, and an annular inwardly-projecting flange, such as G, acting in conjunction with said restrictor B arranged below the top of the wick-tubes to regulate the supply of air to the exterior of the flame; of a conical restrictor mounted within the wick-tubes to regulate the air supplied to the interior of the flame, and a flame-spreader mounted upon the upper end of said restrictor, at or near the level of the top of the hood D, substantially as and for the purposes described.

2. The combination of a straight-through cylindrical chimney with a circular-wick oil-burner having a hood such as D extending above the top of the wick-tubes, a restrictor such as B acting in conjunction with an annular inwardly-projecting flange such as G arranged below the top of the wick-tubes to regulate the supply of air to the exterior of the flame and a restrictor such as H to regulate the air-supply to the interior of the flame acting in conjunction with a "flame-spreader," such as H^X disposed at or near the level of the top of the hood D substantially as and for the purposes described.

3. A circular-wick oil-burner consisting of the combination with circular-wick tubes, of a hood concentrically mounted around the upper part of the wick-tubes and tapering inwardly above the top edge of said wick-tubes, an annular flange extending horizontally inward from the inside of said hood

- above the exterior air-inlet restrictor but below the top of the wick-tubes to regulate the air-supply to the exterior of the flame, a restrictor in the central air-passage to regulate the air-supply to the interior of the flame, and a "flame-spreader" centrally located at or near the level of the top of the hood, substantially as and for the purposes hereinbefore set forth.
4. The combination with a circular-wick oil-burner, having a hood D extending above the top of the wick-tubes, an exterior restrictor B, and an annular inwardly-projecting flange arranged below the top of the wick-tubes, acting in conjunction with said restrictor B to regulate the supply of air to the exterior of the flame; of a conical restrictor mounted within the wick-tubes to regulate the supply of air to the interior of the flame, and a spreader mounted upon said restrictor and acting in conjunction therewith, centrally disposed at or near the level of the top

of the hood D, substantially as and for the purposes described.

5. The combination of a straight-through cylindrical chimney, with a circular-wick oil-burner having a hood D extending above the top of the wick-tubes, an exterior restrictor B acting in conjunction with an annular inwardly-projecting flange G arranged below the top of the wick-tubes to regulate the supply of air to the exterior of the flame, and a restrictor H to regulate the air-supply to the interior of the flame acting in conjunction with a "flame-spreader" H² centrally disposed at or near the level of the top of the hood D substantially as and for the purposes described.

In witness whereof I have hereunto set my hand in presence of two witnesses.

HENRY DARBY.
